DESIGN FOR AN X-RAY CONTROL CABINET

Harry N. Henry, Covington, Ky., assignor to The Kelley-Koett Manufacturing Company Incorporated, Covington, Ky., a corporation of Ohio

Application February 12, 1934, Serial No. 50,686

Term of patent 14 years

To all whom it may concern:

Be it known that I, HARRY N. HENRY, a citizen of the United States, residing at Covington, in the county of Kenton and State of Kentucky, have invented a new, original, and ornamental Design for an X-Ray Control Cabinet, of which the following is a specification, reference being had to the accompanying drawing forming part thereof.

The figure is an oblique elevational view of an X-ray control cabinet showing my new design.

I claim:

The ornamental design for an X-ray control cabinet, as shown.

In testimony whereof I affix my signature.

HARRY N. HENRY.
